CLAIM

The ornamental design for expansion valve with solenoid valve, as shown and described.

DESCRIPTION

FIG. 1 is a perspective view of an expansion valve with solenoid valve showing our new design;
FIG. 2 is another perspective view thereof;
FIG. 3 is a front view thereof;
FIG. 4 is a rear view thereof;
FIG. 5 is a right side view thereof;
FIG. 6 is a left side view thereof;
FIG. 7 is a top plan view thereof; and,
FIG. 8 is a bottom view thereof.

The broken lines shown in the figures are included for the purpose of illustrating portions of the expansion valve with solenoid valve and form no part of the claimed design.
